GARTER

Filed Oct. 18, 1927

Inventor:

Moritz Feldmann

by Kennethas
Atty.

UNITED STATES PATENT OFFICE

MORITZ FELDMANN, OF BARMEN, GERMANY

GARTER

Application filed October 18, 1927, Serial No. 226,892, and in Austria April 30, 1927.

My invention relates to stocking or sock suspenders of the type comprising a garter or band surrounding the leg below the knee and a pad to which a depending strap with a clasp for holding the stocking or sock may be secured. It is an object of my invention to provide an improved appliance of this type.

To this end, instead of the usual connection of the pad and the band by sewing or loops and buttons similar to those of the clasp, or other fastening means, which form as many projections on the pad, I provide as a pad, a block of material having a clasp pivotally mounted in a central raised portion of said block, a structurally integral button shaped protrusion at the lower end of said block, adapted to cooperate with said clasp, and a transverse slot extending through and across the upper end of said block of material for reception of the leg band.

This connection involves the advantages that separate means for securing the band to the pad and the necessity of sewing the band to the pad, are eliminated, and the exchanging of the band is much facilitated.

In the accompanying drawings a device according to my invention is illustrated diagrammatically by way of example.

In the drawings

Fig. 1 is an elevation of the pad with the band inserted therein, only a portion of the band being shown,

Fig. 2 is a section on the line 1—1 in Fig. 1,

Figs. 3, 4 and 6 each illustrate a modified kind of band connecting means, and

Figs. 5 and 7 are sections on the corresponding lines in Figs. 4 and 6, respectively.

Referring now to the drawings, 8 is the pad, and 14 is the band in all figures where these parts are shown. The pad is illustrated as of the usual substantially triangular configuration, but may obviously be designed as desired. A strap with a button 9 and a loop 10 is formed at the base of the pad for the usual clasp, the loop being inserted in a hole 11 of a projection or bear-

ing 12 on the pad 8. The pad is integral with the means for connecting the band to the pad and the clasp so as to make up a self-contained unit. The pad 8 is made of a block of any suitable, preferably resilient or flexible material, rubber, or the like, with or without a lining of cloth. 13 is a longitudinal slot in the upper portion of the pad 8 through which the band 14 is passed.

Referring now to Fig. 3, 17—17 are transverse slots made in the pad instead of the longitudinal slot 13, and the band 14 is passed through the slots so as to partly lie on the front, and partly on the rear face, of the pad 8.

Referring now to Figs. 4 and 5, instead of the slot 13 or slots 17 in the pad 8, a housing 15 is made on the pad and the band 14 is passed within the housing.

Referring now to Fig. 6, the housing is subdivided into three short parts or guides 16 through which the band 14 is passed in succession.

I wish it to be understood that I do not desire to be limited to any definite number of slots or housings for connecting the band to the pad, nor do I desire to be limited in any other respect to the exact details of construction shown and described, for obvious modifications will occur to a person skilled in the art.

I claim:

A garter comprising a leg band and a stocking engaging member slidably mounted thereon; the said stocking engaging member comprising a block of material, a clasp pivotally mounted in a central raised portion of said block of material, a structurally integral button shaped protrusion at the lower end of said block of material, adapted to cooperate with said clasp, and a transverse slot extending through and across the upper end of said block of material for reception of said leg band.

In testimony whereof I affix my signature.

MORITZ FELDMANN.
